WRITING BOARD FOR COIL WIRE BINDERS

Frank Stanley Schade, Holyoke, Mass., assignor to National Blank Book Company, Holyoke, Mass., a corporation of Massachusetts

Application April 6, 1953, Serial No. 346,970

1 Claim. (Cl. 129—1)

This invention relates to a writing or sketch board adapted for use with a coil wire bound pack of sheets, as a spiral wire bound notebook of blank or lined sheets intended for writing or drawing of any nature.

An object of the invention is to provide mechanism on a rigid panel board for the attachment of a coil wire bound notebook thereto and for hanging the same in a position to support the pack of sheets in flat condition at either side of the board or for supporting some of the sheets on one side while other sheets of the stack are swung for flat supporting contact at the other side thereof.

Another object of the invention is to provide mechanism for the ready insertion and removal of a coil wire binder on a writing board and to provide a double hinging action in such a mechanism.

Writing boards of the type herein disclosed are adapted for the user to support the same in his hand, or on his forearm or lap to afford a rigid supporting surface against which the sheets may be laid for writing and other similar purposes and where a table or desk surface is unavailable. The above and other objects and advantages of the invention will be apparent from the following description of a preferred embodiment of the same as shown by the accompanying drawings, in which

Fig. 1 is a partial top plan view with parts cut away of a writing board with a spiral wire bound notebook mounted in position thereon;

Fig. 2 is a partial top plan view of the writing board with the spiral wire notebook of Fig. 1 in a position for removing or attaching the same on the mounting mechanism of the board;

Fig. 3 is a fragmentary perspective view of a modification of the movable retaining member of the mounting mechanism shown at the right of Figs. 1 and 2;

Fig. 4 is an end edge elevation of Fig. 1 showing a spiral wire bound notebook hanging on one side of the board; and

Fig. 5 is a view similar to Fig. 4 showing the notebook hanging against the opposite side of the board.

In the drawings a rigid flat panel board member 1 is shown with a spiral wire notebook having a stack of sheets 2 held between covers 3 on a spiral wire 4. The panel board member may be of wood, plastic, composition board, or any other suitable material providing sufficient rigidity to serve as a supporting surface for writing purposes. A spiral wire bound notebook is herein shown for purposes of illustrating the use of the board but it will be understood that any coil wire type of binding may be used in which the sheets are provided with a series of spaced marginal perforations along one edge and through which a spiral is wound or through which other types of ring wires are passed such as wire coils arranged perpendicular to the axis of the binder element and usually connected by wire portions parallel to the axis.

At one edge of the board 1 a hinge leaf member, as the metallic mounting strip 5, is attached to the marginal portion of the board as by the rivets 6. The strip 5 provides along opposite end portions of the edge and

2

centrally spaced by the recess indicated at 7 a pair of axially aligned pintle receiving sleeve members 8 and 9. The sleeves are formed as will be seen from Figs. 3, 4 and 5 by rolled portions of the strip 5 extending beyond the edge of the panel and inwardly turned back against the edge.

The spaced bearing sleeves are adapted to carry the retaining members on which the coil wire element is hung, as the spiral wire 4. The retaining members are in the form of bent wire rods. In sleeve 8 an inner pintle portion 10 of the retaining rod member at the left as in Figs. 1 and 2 is pivotally mounted with the outer end thereof being reversely bent as at 11 and the outer rod portion 12 lying inwardly extended in closely spaced overlying relation to the outer surface of the sleeve 8. The outer tip end portion of wire 12 is angled as at 13 to provide for the easier entrance and insertion thereof at the end of the spiral coil 4. The wire 12 is also preferably spring tensioned to lie with the outer end portion thereof adjacent the tip 13 pressed toward the surface of the sleeve 8. In Fig. 2 wire 12 is shown substantially parallel to the sleeve by reason of the coils of the spiral 4 being held between the same.

The inner end of the inner pintle wire 10 extends beyond the inner end of the sleeve and the tip 14 thereof adjacent the sleeve is pinched to provide a diametric enlargement for preventing longitudinal movement of the wire 10 in the sleeve.

The oppositely positioned sleeve 9 receives an inner pintle portion 15 (Fig. 2) of the other retainer member, the wire 15 being reversely bent to lie normally along the outer portion thereof in closely spaced overlying relation to the sleeve 9. As shown by Fig. 2 the outer portion of the wire is again reversely bent to form a doubled outer extension as indicated at 17. The free end portion of the extension 17 projects outwardly as at 18 beyond the bend 16 and terminates in an offset finger tab loop as at 19.

At its inner end the inner pintle wire portion 15 projects inwardly into the recess 7 beyond the sleeve 9. The inner end extension indicated at 20 (Fig. 1) terminates in a pinched tip 21 and around said extension is wound a coil spring 22 held between abutments formed by the tip 21 and the inner end of the sleeve 9 for yieldably biasing the wire 15 inwardly of its sleeve 9. As shown by Fig. 2 the offset tab 19 is for finger manipulation of the retaining rod member and the outer withdrawal of the portion 17 beyond the outer edges of sleeve 9. Thus, the coil wire binding element of a notebook to be mounted on the board may be assembled by the telescopic insertion at one end thereof of the wire 12 and the snapping of the portion 17 into the opposite end when the latter end is brought into axial registration therewith. It will be noted that the extension 20 beyond the inner end of sleeve 9 is substantially the same as or of greater length than the portion 17 so that the latter may be withdrawn to an outwardly offset position at the outer end of the sleeve 9.

The outer portions 12 and 17 of the retaining members form in the assembly of a coil wire binder on the board a pair of aligned outer pintle portions for the hinging action of the binder element 4 on said portions as an axis. Thus with the hinged connection of the inner wire portions held in the sleeves a double hinge action is provided for manipulation of the binder. In Fig. 4 the notebook is shown suspended at one side of the board for writing on sheets laid against the surface thereof, while in Fig. 5 the notebook is hung at the other side of the board for writing on sheets laid against the surface of the opposite side. It will be seen that the axis of the coiled spiral wire 4 may be swung to any intermediate position between the two shown and that at a position approximately midway of the two, that is, substantially in the plane of the board, the covers and sheets of the pack may be separated

for disposition on both sides of the board. This may be of advantage in handling the board and particularly where it may be inconvenient to have an uppermost cover and sheets hanging loosely from the edge of the board when writing on or referring to one of the inner sheets of the pack.

In Fig. 3 a modified form of the outer pintle portion of the movable retaining member is shown. The outer pintle at 23 for the coil wire element is a single length of wire overlying the adjacent sleeve 9 and is preferably of the same length as the pintle portion 17 of Fig. 2. The tab means for withdrawing the retaining rod to offset position from the sleeve may then be provided by a pull-tab 24 having an inner opening receiving the wire at the bend thereof for grasping the tab and pulling against the force of a spring 22 mounted on the inner end of the wire as in Figs. 1 and 2. In order to prevent the tab from sliding beyond the bend to interfere with the operation of the inner or outer pintle portions swaged nib sections as at 25 on each side of the tab are provided to form diametrically enlarged abutments to confine lengthwise movement of the tab on the wire. The tab may otherwise be turned freely at the bend to hang therefrom.

What is claimed is:

A writing board for use with coil wire bound notebooks comprising a rigid planar supporting panel member and at one of the end edge surfaces of said panel member mechanism for the releasable mounting of the coil wire element of a notebook to be supported thereon and comprising axially aligned hinge pintle supporting members lying in the plane of said rigid panel and fixed along each end portion of said one end edge surface with the inner ends of said members being positioned in spaced relation, retaining rod members having inner pintle rod portions pivotally supported in said supporting members with the inner tip ends thereof diametrically enlarged to prevent withdrawal from the supporting members and outer pintle

portions of the rod members extending from adjacent the outer ends of said supporting members in closely spaced relation to the outer surfaces of the inner pintle supporting members, said outer pintle portions being freely movable on the axes of said inner pintle portions and at opposite limits of movement being offset from the panel and in overlying relation to the plane of the adjacent face of said panel for the flat superposed relation against either side of the board of a coil wire notebook pivotally hung on said outer pintle portions, the free ends of said outer pintle portions being adapted for telescopic insertion in opposite end sections of the coil wire element of the notebook to be pivotally mounted thereon, a retaining member at one end portion of the panel edge having its inner pintle portion movable to a limited extent longitudinally of the supporting member and extending inwardly beyond the inner end of said supporting member, a coil spring wound around said inner pintle extension and held between the tip end thereof and said inner supporting member to yieldably urge the outer pintle portion thereof inwardly of said panel end, and a finger tab piece mounted on said movable retaining member at the intersection of said inner and outer pintle portions.
